(57) **CLAIM**

The ornamental design for a toy frog as shown and described.

DESCRIPTION

FIG. 1 is a perspective view of a part of toy frog showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the portion labeled 9 in FIG. 1; and,

FIG. 10 is an enlarged view of the portion labeled 10 in FIG. 1.

The broken lines depict portions of the toy frog and form no part of the claimed design.

The dot-dash broken lines depict the bounds of the enlarged views and form no part of the claimed design.

1 Claim, 10 Drawing Sheets
